(57) **CLAIM**

The ornamental design for a belt installation tool, as shown and described.

DESCRIPTION

FIG. 1 is a perspective view of a belt installation tool, showing my new design;

FIG. 2 is a right side view of FIG. 1;

FIG. 3 is a left side view of FIG. 1;

FIG. 4 is a front view of FIG. 1;

FIG. 5 is a top plan view of FIG. 1; and,

FIG. 6 is a bottom plan view of FIG. 1.

The broken lines in FIGS. 1, 5, and 6 illustrate a portion of the design that forms no part of the claim.
